UNITED STATES PATENT OFFICE

2,637,383

AUTOMATICALLY OPERATED JACKKNIFE
WINDOWWilliam A. Bowman, Baltimore, Md.
Application July 10, 1950, Serial No. 172,955

3 Claims. (Cl. 160—188)

1

This invention relates to building equipment and more particularly to mechanism for the mechanical and automatic operation of windows used in various types of structures.

The opening and closing of conventional windows has received considerable attention, but the results attained have not been satisfactory. To meet this situation, this invention has been developed and used under practical conditions to assure of its meeting the requirements expected from the daily use of such equipment. It consists of a jack-knife window structure modified in some particulars from that shown in Patent No. 2,513,278 and application Serial No. 81,375, filed March 14, 1949 and now abandoned, that is 15 operable by motor power, controlled manually, or by action of rain or wind. Part of the control is automatic while the other parts are influenced by the manipulation of the user to suit himself, as circumstances may require.

It is an object of this invention to provide a new and improved window and operating mechanism that will avoid one or more of the disadvantages and limitations of the prior art.

Another object of the invention is to provide a new and improved window-operating mechanism that will have features of mechanical cleaning; closing when it rains or the wind becomes excessive; and opening and closing under the action of a motor.

A further object of this invention is to provide a new and improved window operating mechanism that can operate a jack-knife window in a positive and effective manner, through the use of motor mechanism under the control of an operator.

It is a further object of this invention to provide a new and improved window operating mechanism that will seal the window in locked position against air leakage and make same burglar proof.

It is a further object of this invention to provide a new and improved jack-knife window that can be raised or lowered manually or mechanically to predetermined positions and retain same in said positions.

It is a further object of this invention to provide a new and improved window having a device for automatically closing the window through the action of rain or excessive wind storms.

It is a further object of this invention to provide a new and improved jack-knife window with means cooperating with the screws operating in one direction to align the window units with each

2

other and when the rotation of the screws are reversed to move the units out of alignment.

Other objects of the invention will be indicated as the invention is more fully described.

For a clearer comprehension of the invention, its objects principles and mode of operation, reference is made to the accompanying drawings, which in conjunction with the following description illustrate a particular form of structure, as an example, not as a limitation. The claims show the scope of the invention.

Referring to the drawings:

Figure 1 is a front elevation of a window unit embodying this invention;

Figure 2 is an inside elevation of Figure 1;

Figure 3 is a perspective view of the unit with its window shown partly opened in jack-knife fashion;

Figure 4 is a sectional view taken transversely across the window on line 4—4 of Figure 1;

Figure 5 is a sectional elevation on line 5—5 of Figure 4;

Figure 6 is a sectional elevation transversely viewed on line 6—6 of Figure 5;

Figure 6A is a detail showing the hinge connection between the window sashes;

Figure 7 is a detail of the storm sash catch used in this embodiment;

Figure 8 is a section on line 8—8 of Figure 7;

Figure 9 is a plan view of the talon mechanism;

Figure 10 is a side view of Figure 9;

Figure 11 is a sectional plan view on line 11—11 of Figure 1;

Figure 12 is a longitudinal sectional view of line 12—12 of Figure 11; and

Figure 13 is a transverse sectional view on line 13—13 of Figure 12.

Similar reference characters refer to the same parts throughout the drawings.

For a better understanding of the invention and the objects thereof, attention is called to the drawings, in which a particular structure of the invention is illustrated. In conjunction with the following description, these drawings outline the features of the device, while the claims indicate the scope of the invention.

The structure in the drawings indicate a window embodying the invention and has the general appearance of a conventional window sash frame, with a sill underneath. However, the frame is made of channels 10, 11, 12, and 13 for the upper cross frame, the left and right side frame member and the sill respectively. The upper frame member or channel 10 is boxed in and contains the mechanism for controlling the flow of the sash cleaning liquid sprayer as well

as that for the rain and wind sash closer. The left side channel 11 is also boxed in and contains an operating screw 14 connected with lower window sash 15, for raising and lowering it in jack-knife fashion, outwardly from the window frame. The right hand channel 12 is also boxed in and contains the screw drive 16 the miter gear 89 and long shaft 17 driving them.

The sill channel 13 is also boxed in and contains the main operating motor 18, its shaft 19 and the gear 21 all connected together. A clutch 20, operated by a solenoid 22 connects and disconnects the shaft 19, from the stub shaft 23. The stub shaft 23 has a miter gear 24 keyed to it and meshed into the adjacent miter gear 99 mounted on the shaft 17. The details of these mechanisms will be enlarged upon as the description is proceeded with.

The principal functions of the window embodying this invention are:

(A) *Operation.*—Including open and closing actions of the window sashes, in jack-knife manner;

(B) *Washing.*—The use of cleaning liquid on the glass and its removal with the accumulated dirt by a mechanically operated squeegee mechanism when it rains or high winds prevail;

(C) *Wind and rain control.*—An arrangement for operating the window sashes and closing them when the outside wind and rain become excessive;

(D) *Weatherstripping.*—An arrangement provided for sealing the window rain tight and render it burglar proof when closed;

(E) *Incidental refinements.*—To provide for an effective closure of the sashes, so that detrimental conditions arising from exterior or accidental influences will be anticipated and offset.

The diagram in Figure 14 indicates the electrical connections utilized for producing these functions and will be explained later.

Main operating mechanism

The main operating mechanism of this device is employed in the opening and closing of the window sashes in jack knife fashion. In Figure 12, the mechanism is shown located in the sill channel or compartment 13. When the motor 18, Fig. 6, is running, it rotates its shaft 19 and the clutch 20 keyed to it. The gear 21 is loosely mounted on the shaft 19 and is rotated when engaged by the clutch 20 and rotates the gear 25 and shaft 29, which also operates miter gears 28. The miter gears 28 mesh with miter gears 31, which in turn rotate the vertical screws 14 and 16 on the left and right sides of the window sashes 15, 33. The various shafts are suitably journaled in the window frame. The screws 14 and 16 have their end portions extended into cylindrical rubber rollers 30 which they rotate on their axes within the walls 32 provided in the channels 11, 12, to frictionally contact the window sashes. The rollers 30 frictionally rub against the side faces or edges of the sash frames when the sashes 15, and 33 are closed by the screws 14 and 16 to complete the window closure against the surrounding channels. The rollers 30, do this when the screws are rotating in the direction adapted for forcing the sashes into closed position. If the rollers and screws are turned axially in the reverse direction while holding their axial positions, they will rub on the sash and open the sashes from their vertical dead-center closed position towards the jack-knife opening position, as long as they can roll and frictionally rub the side surfaces of the sash frames. Thus it may

be noted, that the initial opening movement of the window is easily accomplished and avoids difficulties of the pair of sashes locking on dead-center, which the sashes are on when closed.

5 This is due to the rubbing and lateral propelling action of the rollers against the sash frames, which are preferably knurled.

The window operating mechanism extends through the lower sash bar 35 and is reciprocable from the middle outwardly. It consists of two rods 36 having talons or forked outer ends 38. A collar 39 is rigidly secured on each of the inner end portions of the rods, against which a coil spring 37 presses tending to spread them apart.

15 When they are spread apart the forked ends 38 engage with the root of the threads of screws 14 and 16 and they are raised or lowered as the screws rotate. The rods 36, which carry the talons 38, being positioned in the bar 35 raise the

20 latter and sashes 15 and 33 with them. When the lower sash 15 is lifted, it moves outwardly in jack-knife fashion and since it is hinged on the upper sash 33, it also moves the latter angularly outwards on the hinges 40 that support it on channels 11 and 12, respectively, Fig. 5. When the window sashes are fully extended or open, they trip a limit switch (not shown) and stop the motor 18. Likewise a limit switch (not shown) opens the circuit when the sashes are closed.

25 30 The talons 38 have a form like a fork bent to engage against the threads of the screws 14 and 16 and move with the latter when the screws are rotated. The mechanism 34 is operated to disengage the talons 38 from the screws 14 and 16

35 when a spreader mechanism 43 is used. The mechanism 43 includes a cam member 44 rotated by a handle 45 mounted on a plate 46 from which it extends. The plate and handle are set on the inside or rear face of the sill channel frame 13

40 where they can be reached by the user of the window from inside the structure. When the cam member 44 is rotated sufficiently, it strikes the projecting bases 47 of a pair of bifurcated elements or jaws 48 and swings them on pins 49 so they will press against the collars 39 and pull the rods 36 and talons 38 away from and out of engagement with the screws 14 and 16. When this happens the window sashes if opened, will come down to a closed position, by reason of the weight of the sashes. This is used for quick or manual opening or closure of the window.

45 50 For a normal closure of the window, the motor 18, is thrown into the electrical circuit in reverse so the screws will rotate in the opposite direction to that mentioned for opening the window. The screws 14 and 16 turn and through the talons 38 and mechanism 34 lower the sash, relatively slowly.

Wind and rain operation

55 60 The sash operating mechanism will also operate to lower the window when a wind and rain switch 50 throws the motor 18, into circuit. The mechanism is simply a vane 51 extending outwardly from the upper channel 10 and delicately suspended on a spindle 52, that permits its movement laterally to contact an electrical conductor (not shown) and when it does so, connects up the motor with the electrical circuit so it will 65 close the sashes as already described. The same vane also is operated by rain, snow or hail in a similar manner by tilting the spindle. The vane 51 is preferably cupped to facilitate the catching of the rain thereon so its weight may be increased 70 sufficiently to close the circuit.

Washing operation

The glass on the outside of the sashes are washed and cleaned by sprinkling water over them through the action of a solenoid-operated valve 55 that feeds water from a water supply, into a piping 56 to a sprinkling tubing 57 having a flared lip and placed horizontally about the upper sash 33. The tubing pours the water over the outside of the upper sash 33 in sufficient quantities to flood and clean it off. The stream of water continues until it flows down over the outer window glass of the lower sash 15. The control of the water supply is provided for by using a small electric motor (not shown) on which a conventional timing gear mechanism is attached. This timing arrangement allows the water to flow for a period of three minutes and stops the flow, by closing the solenoid-operated valve 55. When the water supply is turned on, the squeegee and its operating mechanism is also started through the movement of the clutch 20 so the motor 18, will rotate the stub shaft 23 and the miter gears and screw threaded shafts 91 and 94 through shaft 17, miter gears 89 and 92 and jack shaft 93 supported in and co-axial with the trunnions or hinges 40. The lower end of the shaft 91 is fitted with a miter gear 95 that meshes with a miter gear 96 to drive a shaft 97 and its miter gear 98 and miter gear 99 connected to threaded shaft 94. The shaft 103 is driven from shaft 97 through spur gears 102 and through miter gears 104 rotates the screw threaded shafts 100 and 101, raise and lower the cross-member 59. This is done through the threaded portions of the cross-member following the rotation of the threaded portions of the shafts 91, 94, 100 and 101. Each of the cross-members 59 carries a rubber strip 61 that presses against the outside surfaces of their respective window glass and cleans them off, while moving up and down thereon.

The motor 18 rotates in one direction to raise the squeegees and is reversed to lower them. This is accomplished through the action of a ratchet relay and its switches at the end of each travel stroke. The squeegees continue their up and down travel until turned off by a switch (not shown).

Weather stripping

The weather stripping or seal arrangement is mainly provided for by closing the cracks left between the sides of the sashes and the window frames. The sashes to operate efficiently and effectively, must have enough clearance to operate easily. When closed the extra room provided must be shut off to prevent drafts and burglars from opening window from outside and other objectionable reactions to take place. To accomplish this, a pair of vertical 90° semi-circular weather strip or seals 62 are journalled in the upper and lower channels 10 and 13 so they can rotate on their axes towards the face of the sash frames and lap over the cracks mentioned. If rotated 90° in the opposite direction, they revolve out of the way of the sash frames and avoid obstructing its opening and closing movements while jack-knifing. The weather strips or seals are actuated by a solenoid 63 which operates an arm 105 connected to another arm 106 pivoted at 115. The arm 106 connects and operates links 107 and 108 connected for manual operation. The movement of the disc 109 also moves the rack gears 111 and through gears 112 operate the shafts 113 for rotating the seals 62. The handle 75

110 projects through a slot 116. The window opening and closing screw 14 is preferably made with left hand threads and screw 16 made with right hand threads. The squeegee operating screws 91, 94, 100 and 101 are made with right and left hand threads as noted in Figure 5 of the drawings.

When it is desired to raise the window a conventional switch closes the circuit to the solenoid 63 which rotates the seals 62 and unlocks the window and at the same time starts the motor 18 which raises the window. When it is desired to lower the window the switch is moved to another position and reverses the motor 18 and closes the window.

Structural features

The window has a number of conspicuous structural features in addition to those already referred to. The sashes 15 and 33, are brought closely together by hinging them at 103, Fig. 6a where they join and rounding their contacting surfaces 65, 66 so they can move through their jack-knife motions without binding or producing an open crack therebetween. The hinging 64 consists of a hinge plate 125 at each side of the sashes 15 and 33 in the neighborhood of the contact surfaces 65, 66. Each plate 125 is secured by screws 126 to the lower portion of the side of sash 33 and extends downwardly to a point below the upper edge of sash 15. The plate has an opening near its lower end to receive the end of shaft 103 therein and act as a bearing therefor. Thus, when the window jackknives, the end of shaft 103 acts as a pivot for the opening and closing movements of the sashes. Similarly the upper bar 67 of the upper sash 33 is rounded where the contact surfaces 68, 69 meet. Further the joint is covered by a flared strip 70 extending across the window above the upper sash 33.

The sashes 15 and 33 are arranged for the use of storm sashes 71, 72 therein respectively. The latter are glazed in rectangular frames 73, 74 that are flanged to fit flush in the sashes 15 and 33, and be held therein by catches 75.

The squeegees are guided in grooves 76 in the vertical sides of the sashes 15 and 33 and after use always return to the lower bars of the sashes and remain there.

An electrical control box not shown houses the necessary relays, some of the switches, water control motor and other controls not located in the window base as it is not necessary to house these units since they may be located in the base or other portions. A conduit 110 is used to carry the control wires through the frame. Bearings (not shown) are attached to the upper ends of the screws 14 and 16 and are tensioned to force the rollers 30 outwardly against the side of the sash and allow for wear in the rollers, so they may be frictionally tight for kicking the sash at its joint outwardly off dead-center when opening the window and for drawing the joint back on dead center when closing the window so the seals 62 may snap back to lock the windows. While but one general form of the invention is shown in the drawings and described in the specifications, it is not desired to limit this application for patent to this particular form, as it is appreciated that other forms of construction could be made that would use the same principles and come within the scope of the appended claims.

Having thus described the invention, what is claimed is:

1. In combination with a window frame, a

pair of vertically aligned sashes, hinging means between said sashes along their horizontal meeting edges, hinging means between the upper sash and the frame, means for initiating opening movement of the sashes out of vertical alignment consisting of a vertical screw carried by the frame, a roller carried by said screw and pressing against the vertical edge of the upper sash, means for rotating the screw, means cooperating with the initiating means consisting of a slideable element carried by the lower sash, said element having a forked end engageable with the root of the threads of the said screw, whereby said element will move upwardly and downwardly with the rotation of the screw, forcing outward and inward movements of the sashes about their common hinging means, and means for controlling the engagement and disengagement of said element with said screw.

2. In combination with a window frame, a pair of vertically aligned sashes, hinging means between said sashes along their horizontal meeting edges, hinging means between the upper sash and the window frame, means for initiating opening movement of the sashes out of vertical alignment including a vertical screw carried by the frame, a roller carried by said screw and press-

ing against the vertical edge of the upper sash, means for rotating the screw, and means to complete opening movement of the sashes.

3. In combination with a window frame, a pair of vertically aligned sashes, hinging means between said sashes along their horizontal meeting edges, hinging means between the upper sash and the window frame, motor-operated means for initiating opening movement of the sashes out of vertical alignment, said last-named means including a vertical screw carried by the frame, a roller carried by said screw and pressing against the vertical edge of the upper sash, connecting means between the motor and the screw, and additional means cooperating with the aforementioned means to complete opening movement of the sashes, said additional means including an element carried by the lower sash and engageable with the screw and translatable thereby.

20 WILLIAM A. BOWMAN.
